PROTECTOR GUIDE FOR DRESSING SHOES

John M. Mayer, Johnsonburg, Pa.

Application September 26, 1934, Serial No. 745,516

6 Claims. (Cl. 36—72)

The present invention relates to the art of dressing or polishing shoes, especially shoes the extension sole-edges of which are not intended to be the same color as their uppers and shoes ordinarily referred to as two-tone shoes, and particularly contemplates a shield or combination of shields within the scope and type hereinafter described, adapted to be used during the dressing or polishing of such shoes to prevent intermixture of colors and to assure and make easily possible polished shoes where there is no smearing of one color over on the other and where one color stands out in sharp, clean contrast to the other, even along the line of demarcation between the two colors. My shield is preferably made of celluloid, bakelite, or similar cellulosic or phenolic condensation product, but may be made of other stiff materials.

For a quick understanding of illustrative embodiments of my invention, reference is made to the accompanying drawing in which:

Figure 1 is a plan view of a shield adapted to completely encircle a shoe, its inner edge being designed to fit the curvature of the shoe between the sole and upper thereof;

Figure 2 is a detail view taken on line 2—2 of Figure 1, indicating how the fastening works which holds together the two sides or wings of the shield;

Figure 3 is an enlarged detail view taken along line 3—3 of Figure 1;

Figure 4 shows another embodiment of the shield shown in Figure 1;

Figure 5 shows a modification of the embodiment shown in Figure 4;

Figure 6 shows in perspective a shoe with a shield of stiff material of the type shown in Figure 1 fastened therearound and showing a shield, having the contour of the edge between the two colors on the upper, drawn thereover and anchored between the shoe and the shield of stiff material;

Figure 7 is a detail view in cross-section, taken on line 7—7 of Fig. 6, showing the shield, which passes over the upper, anchored against the sole by the stiff shield;

Figure 8 is a detail view in section taken on line 8—8 of Fig. 7, showing the flexible shield and gripping means holding it in place on the toe of the shoe.

Referring more in detail to the drawing in the several figures of which like numerals denote similar parts, the two wings of the stiff shield or guard shown in Figure 1 are pivotally connected at point 1. Elongated slot 2 in one wing thereof

permits lateral adjustment of one wing with respect to the other and the tension spring 3 acts to maintain the inner edge of the shield in firm, tight engagement with the shoe between the sole and upper thereof, the pivot 1 sliding in the slot 2 in response to the force of spring 3. There is an overlapping of the shoe encircling edge by the lips 4 and 5 at the back and front of the shoe respectively. This is to assure that there will be no gap in the shoe-encircling edge of the shield 10 or guard even though the pivot 1, acting against spring 3, is at the upper end of slot 2, and even though the fastening 6 at the front of the stiff shield is fastened in its widest adjustment. The lip 5 on the upper wing of the guard or stiff shield 15 passes above the coacting lip 5 of the lower wing but the arm of the fastening 6 passes below the coacting body portion of the lower wing; hence the upturned end of the arm of the fastening is securely held in the desired slot thereof, due to 20 the stiffness of the shield itself. The shield, when applied to a shoe, as can be seen from the drawing, is in the form of a band of material extending around the shoe and having an inner opening of contour to conform to the curvature 25 around the edge of each shoe between the sole and upper thereof.

While it is preferred that a shield be made up particularly for each style and size of shoe, and be enclosed with the shoes at the time of sale 30 to the customer, yet it is not absolutely necessary for a separate design and size of shield to be made up for each style and size of shoe. The sharp inner edge of the stiff shield or guard, as illustrated in Figure 3, need not be pressed in as far 35 as possible in the depression between the sole and upper of the shoe to effectively prevent the colors from getting intermixed. Hence it is possible to use one design of guard on several styles of shoes which do not differ too greatly from one another. 40 Also the automatic adjustment at the rear of the stiff shield or guard and the adjustable fastening at its front make a single shield further adaptable for use on a wider range of varying styles and sizes of shoes.

In the dressing or polishing of two-tone shoes, for example shoes having black and white uppers or brown and white uppers, I provide shields preferably of stiff cloth or canvas or other fairly flexible material, cut to the pattern of the marginal line between the two colors, as shown in Figure 6. The shoe shown is of the wing-tipped style. The toe and heel portion are usually the heavier color, for example black, and the rest of the upper is usually the lighter color, for exam- 45 50 55

ple white. The heavy colored portions are usually sewed on top of the lighter colored portions, with the result that there is a rise in the surface along the line of demarcation between the two colors. The greater difficulty is usually encountered in cleaning and whitening the shoe right up to the black without smearing the black, it being less difficult to blacken the shoe satisfactorily along the edge of the white without smearing the white. (This is undoubtedly partly because the black portion is raised above the white.) Accordingly I show the flexible shield 8 in the drawing covering a portion of the toe or heavy colored portion 10 of the shoe along the edge of the white or lighter colored portion 11. The extended ends of the flexible shield are anchored between the stiff shield or guard and the shoe. Likewise with the shield shown at the rear of the shoe; it covers the edge of the black or heavy colored portion along the white and its extended ends are anchored between the stiff shield and the shoe, holding the same tight. The rear shield, which is continuous from one side to the other of the shoe, hooks over the top of the back by hooks which may take the form of a continuous turned down piece of stiff material anchored in the flexible shield, as can be seen in Figure 6. Both the back and toe shields preferably have tiny brads or hooks along their edges adjacent the lighter color of the upper, such as brads 9, illustrated in connection with the toe portion, which are adapted to abut the edge of the overlapping material and thereby make it easier to adjust and keep in place said flexible shields.

Of course, flexible shields to cover an edge of the white along the black can readily be supplied, if desired, and are contemplated within the scope of this invention. For example the toe shield shown in the drawing could readily have the contour of its front edge styled so that when the shield is slipped back on the white portion, the front edge of the shield will fit against the edge of the overlapping piece of black material.

In place of being held firmly in the desired position on the upper by the stiff shield or guard, as shown in the drawing, the toe and heel shields may be fastened by joining the ends beneath the sole of the shoe, for example by a buckle or an elastic or rubber connection.

Figure 4 shows, as a modification of Figure 1, a more simple stiff shield or guard, having no pivots, fastenings or moving parts. It consists of a single solid piece which may be made by a simple stamping operation or by a single casting operation. The guard or stiff shield, in addition to having a curvature in the plane of the paper as shown (this is, of the shoe-contacting edges thereof), of course also has a height-wise curvature to correspond with the height-wise curvature of the line of union between the sole and upper of the shoe for which it is to serve as a protector. This height-wise curvature of the line of demarcation between the sole and upper of the shoe, in passing from the toe of the shoe up along the instep to the heel thereof, and also the similar and corresponding height-wise curvature of the guard which fits therein, are illustrated in the perspective view of the shoe and shield presented in Figure 6. Being made of sheet celluloid, or some such material, the shield can readily be bent a substantial amount to accommodate variations in height-wise curvature.

Figure 5 shows a modified form of the stiff shield or guard shown in Figure 4 and possesses all the same curvatures but in four segments.

The letters *a*, *b*, *c* and *d*, both on Figures 5 and 4, show the respective portion of the shoe which each curvature of the guard shown in Figure 5 is adapted to fit.

In place of being divided into four segmental curves, such a stiff shield or guard as shown in Figure 5 may have only three or may have five or six or more segmental curves, as desired. In guards of such type, there is preferably stamped along each segmental curve a designation which will show at a glance which curve of the shoe it is adapted to fit. Guards of this type and of the type shown in Figure 4, as well as the type shown in Figure 1, can also be conveniently included with the shoes to the customer, and thus the practical problem of getting to the customer the most suitable shield or guard can be conveniently solved.

A guard of the type shown in Figure 5 can readily be made to fit a rather wide range of styles, thus making it possible for a purchaser to select a workable guard from a group of general styles without the guard being designed solely for that type of shoe.

Much of the sales resistance heretofore encountered in selling white shoes, having black or natural leather colored sole edges, for example, and in selling two-tone shoes has been due to the difficulty which the customer knew he would have in keeping such shoes looking clean, new and well-kept. It has been a painstaking and almost nerve-racking job to get a pair of shoes, having two colors, polished or dressed so that they look clean and neat and like new. Almost invariably the white or light part of the shoe is not sufficiently cleaned adjacent the darker color; also there is usually not enough polish or dressing applied adjacent to the darker color, nor is it sufficiently shined or smoothed out. As a result of this there is usually a gradual fading out of the lighter color as it approaches the darker color, and a resultant smearable appearance. While everyone with any normal sense of style and neatness would like to have his shoes cleaned and polished so that there would be a sharp, clean line of demarcation between two colors, either on the upper itself or between the sole and upper, as the case may be, yet because of the lack of facilities heretofore provided for such purpose, such persons were forced to forego such desire. Often these circumstances have persuaded them to forego their desire to wear white shoes (with black or leather colored sole edges) or sport shoes. The tediousness of the task and time required to keep such shoes looking well was prohibitive in many instances. Other persons, whose desire to wear white or two-tone shoes outweighed their insistence on neatness, have worn such shoes at a sacrifice of appearance and neatness.

My invention provides means for quickly and easily cleaning and dressing such shoes, without tediousness or meticulousness. A sharp line of demarcation can be made between colors, and each color can be uniformly cleaned and polished right up to the very border line of the other. My shields, in their various forms, i. e. the stiff shields or guards and/or the flexible shields, can be applied in a moment's time and as quickly removed when the polishing operation is completed. My guard and shield are adapted to be made in compact form and of a cheap and durable material.

I further contemplate that my guard and/or flexible shield, particularly when supplied by the

manufacturer to the customer with each new pair of shoes of the type herein concerned, shall also serve as a medium for advertising.

Various modifications of my invention will be-
5 come readily apparent to others from this speci-
fication and the appended drawing. All such
modifications are herein contemplated as part of
this invention and within the scope of the ap-
pended claims.

10 What I claim is:

1. As an article of manufacture, a guard for
use in dressing shoes comprising a solid approxi-
mately flat material having edges thereof sub-
stantially inflexibly curved to fit the curves
15 around the periphery of a particular size and
style of shoe in the depression or line of de-
markation between the sole and upper thereof.

2. As an article of manufacture, a guard for
use in dressing shoes comprising a solid piece of
20 stiff material having its periphery made up of a
plurality of segmental curves, each segmental
curve corresponding substantially to a segment
of the curvature around the edge of a shoe be-
tween the sole and upper thereof, said plurality
25 of segmental curves including substantially ev-
ery said curvature around the edge of a particu-
lar size and style of shoe and each of the said
segmental curves of said solid piece of stiff ma-
terial being located in substantially fixed relation
30 to other curves thereof.

3. As an article of manufacture, a guard for
use in dressing shoes comprising an elongated
piece of stiff material having both side edges
thereof curved, one side edge curved to corre-
spond to substantially the entire curvature be-
35 tween the sole and upper of a shoe along sub-
stantially the whole right side thereof and the
other side edge curved to correspond to substan-

tially the entire curvature between the sole and
upper along substantially the whole left side
thereof.

4. As an article of manufacture, a guard for
use in dressing shoes comprising a solid, thin, ap-
proximately flat, elongated piece of stiff ma-
terial having both side edges thereof curved, one
edge curved so as to fit the curvature between
the sole and upper of a shoe along substantially
the whole right side thereof, and the other pe-
10 ripheral edge being curved so as to fit the curva-
ture between the sole and upper along substan-
tially the whole left side thereof.

5. As an article of manufacture, a guard for
use in dressing shoes and which comprises a piece 15
of relatively stiff material being substantially
poly-sided, each side edge being shaped to cor-
respond substantially with a portion of the curva-
ture around the edge of a shoe between the sole
and heel and the upper thereof, each of said 20
shaped edges of said guard being relatively stiff
and located in substantially fixed relation to the
edges thereof.

6. As an article of manufacture, a guard for
use in dressing shoes and which comprises a piece 25
of relatively stiff material having four sides, one
side edge being shaped to correspond substan-
tially with the curve of the in-step portions of the
shoe between the sole and upper thereof, another
edge similarly corresponding with portions at the 30
heel of the shoe and the other edges substantially
corresponding, respectively, to the opposite side
portions between the sole and upper at the vamp
and toe of the shoe, each of said shaped edges of
35 said guard being relatively stiff and located in
substantially fixed relation to the edges thereof.

JOHN M. MAYER.
